UNITED STATES PATENT OFFICE

2,458,177

POWER STEERING AND PROPELLING
MECHANISM

John Frank Johnson, Ludington, Mich.

Application February 28, 1945, Serial No. 580,247

17 Claims. (Cl. 115—35)

1

The main objects of this invention are:

First, to provide a propeller control apparatus which adapts the propeller for reversing and steering either in reverse or forward directions.

Second, to provide a control apparatus of this character in which the propeller may be swung throughout 360 degrees.

Third, to provide a control apparatus having these advantages which is simple in structure and easily operated, the mechanism being driven from the prime mover.

Fourth, to provide an indicator means for use in an apparatus of the character described in which the positions of adjustment of the propeller, both forward and reverse, are indicated, showing the course of the ship both forward and reverse, the indicating pointers being so arranged that one is concealed when the other is in view of the operator.

Objects relating to details and economies of the invention will appear from the description to follow. The invention is defined and pointed out in the claims.

Preferred embodiments of the invention are illustrated in the accompanying drawings, in which:

Fig. 1 is a fragmentary side elevation of a control apparatus embodying the invention, certain of the parts being shown conventionally.

Fig. 2 is a fragmentary view mainly in vertical section showing details of the propeller and its support and the driving connections for the propeller and certain details of the steering mechanism.

Fig. 3 is an enlarged fragmentary view partially in horizontal section on line 3—3 of Fig. 2.

Fig. 3-A is a fragmentary view partially in horizontal section illustrating details of the driving and reversing gearing for controlling the propeller support.

Fig. 4 is an enlarged view mainly in vertical section on line 4—4 of Fig. 3 showing details of the indicator.

Fig. 5 is a fragmentary view partially in section on the broken line 5—5 of Fig. 4.

Fig. 6 is an enlarged fragmentary view partially in section on line 6—6 of Fig. 3.

Fig. 7 is an enlarged section on line 7—7 of Fig. 3.

In the accompanying drawings, no attempt has been made to illustrate the parts in their relative proportion and certain of the parts are shown conventionally.

In the accompanying drawings 1 represents the prime mover in the form of an internal combustion

2

engine. The shaft 2 of the propeller 3 is mounted in a support 4 rotatable upon and depending from the bearing member 5 carried by the gear box 6. The engine shaft 7 is provided with a beveled gear 8 meshing with a gear 9 on the propeller shaft 10. The particular details of the driving connection form no part of the present invention except that the propeller support designated generally by the numeral 4 is rotatable and its axis is perpendicular to the propeller shaft. The lower end of the shaft 10 is connected to the propeller shaft by the coaxing gears 11.

The rotatable propeller support is provided with a worm gear 12 arranged in a suitable housing 13, this worm gear being driven through the worm 14 on the shaft 15. This shaft 15 extends into the gear box 16 and is provided with a driven beveled gear 17 meshing with a pair of driving gears 18 rotatably mounted on the shaft 19. The shaft 19 is connected to a driving shaft 20 by means of belts 21 and 22 and suitable coacting pulleys, this properly gearing down the shaft 19 to constitute a driving shaft for the propeller adjusting mechanism.

The shaft 19 is provided with a double cone driving clutch element 23 mounted thereon for axial movement but rotating therewith. The gears 18 are provided with coaxing cone clutch elements 24, the clutch element 23 being selectively engageable with either clutch element 24 and thereby driving the gear 17 in either direction.

The shaft 15 is provided with a bearing 25 for the pulley 26. This pulley has an elongated hub 27 with a diagonally disposed slot 28 therein receiving the pin 29 on the bearing so that as the pulley is rotated in either direction from the initial position shown in Fig. 3 it is shifted axially in one direction or the other. This axial movement is utilized to control the shiftable clutch member 23, the shifting lever 30 being provided with a suitable fork engaging the shifting collar 31 having ball bearing connection with the clutch element 23. This shifting lever is pivoted at 32 and is connected by the link 34 to the hub of the pulley 26, the connection being effected by means of the ring 35 engaging the forks 36 on the lever 34.

The pulley is rotated on its bearings by the cable 37 extending from the pulley 28 of the steering wheel 39 so that as the steering wheel is rotated in either direction from its central or straight-ahead position, the pulley 26 is rotated and shifted axially thereby engaging the driving clutch element with either one or the other of

the gears 18 thereby driving the shaft 15 and through the worm 14 thereon the gear 12 and thereby rotating the propeller support in one direction or the other.

In the embodiment illustrated the propeller support may be rotated through 360 degrees so that the propeller may not only be adjusted as a steering propeller in a forward direction but also for steering in reverse.

In order that the helmsman may know just what position the propeller is in, I provide an indicator consisting, in the embodiment illustrated, of a casing 40 having a front panel 41 of glass. Spindles 42 and 43 are mounted in this casing in spaced parallel relation and connected by the driving gears 44. Each spindle is provided with a pointer 45 arranged on the spindles as shown in the drawings. The gears 44 are in meshing relation with a result that one spindle is driven in one direction and the other in the opposite direction. The casing is provided with a front 46 having segmental oppositely curved slots 47 therein, there being a slot associated with each pointer. Each slot has a scale or indicia associated therewith.

It will be noted that with this arrangement only one pointer is visible at a time. The pointer associated with the upper slot would indicate the forward positions of the propeller while the other would indicate the reverse positions of the propeller. It should be noted that the forward position of the pointer is the reverse of the propeller, whereas the stern position is in the same relation to the propeller. The indicators are driven from the shaft 15 through the flexible shaft 48 which is connected to the end of the shaft, as shown in Fig. 3, and provided with a worm 49 (Fig. 5), in driving engagement with one of the gears 44. This flexible shaft is also shown conventionally.

With this arrangement of parts, a power drive is provided for the control mechanism and very little effort is required on the part of the steersman or helmsman. The control device enables a universal control of the propeller and the control mechanism may be very readily embodied in or adapted to existing types of propellers.

I have illustrated and described my invention in a very practical embodiment thereof. I have not attempted to illustrate or describe various adaptations and modifications which I contemplate and which might be desirable for particular propellers having structural features peculiar thereto as it is believed that this disclosure will enable those skilled in the art to embody or adapt my invention as may be desired.

Having thus described my invention, what I claim as new and desire to secure by Letters Patent, is:

1. The combination of a propeller provided with a support rotatable through 360° on an axis perpendicular to the axis of the propeller, a worm gear on said propeller support, a driving worm coacting therewith, a shaft for said worm provided with a beveled driven gear, a pair of beveled driving gears disposed in opposed coacting relation with said beveled driven gears and provided with opposed cone clutch elements, a driving shaft for said driving gears, a driving cone clutch element mounted on said driving shaft between said driven clutch elements for neutral positioning or selective engagement therewith, a bearing mounted on said worm shaft provided with a projecting pin, a pulley provided with a hub rotatable on said bearing and having a cam slot coacting with

said pin whereby rotation of the pulley imparts axial movement thereto, a shifting lever for said driving clutch member, a link connecting said pulley hub to said shifting lever, a steering wheel having cable connection to said pulley, and an indicator comprising a casing having curved segmental oppositely disposed windows having indicia associated therewith, spindles mounted on said casing and each provided with a pointer disposed in the same relation thereon, each pointer being associated with one of the windows, meshing gears connecting said spindles whereby the points are driven in opposite direction, and a driving connection for said worm shaft to one of said spindle gears whereby the forward position of the propeller is indicated by one pointer throughout a range of 180° and the other pointer indicates its reversing positions throughout a range of 180°.

2. The combination of a propeller provided with a support rotatable through 360° on an axis perpendicular to the axis of the propeller, a worm gear on said propeller support, a driving worm coacting therewith, a shaft for said worm provided

25 with a beveled driven gear, a pair of beveled driving gears disposed in opposed coacting relation with said beveled driven gears and provided with opposed clutch elements, a driving clutch element mounted between said driven clutch elements for neutral positioning or selective engagement therewith, a bearing mounted on said worm shaft, a pulley provided with a hub rotatable on said bearing and having a cam engagement therewith

30 whereby rotation of the pulley imparts axial movement thereto, a shifting lever for said driving clutch member, a link connecting said pulley hub to said shifting lever, a steering wheel having cable connection to said pulley, and an indicator comprising a casing having curved segmental oppositely disposed windows having indicia associated therewith, spindles mounted on said casing and each provided with a pointer disposed in the same relation thereon, each pointer being associated with one of the windows, meshing gears connecting said spindles whereby the pointers are driven in opposite directions, and a driving connection for said worm shaft to one of said spindle gears whereby the forward positions of the propeller are indicated by one pointer throughout a range of 180° and the other pointer indicates its reversing positions throughout a range of 180°.

4. The combination of a propeller provided with a support rotatable through 360° on an axis

perpendicular to the axis of the propeller, a worm gear on said propeller support, a driving worm coacting therewith, a shaft for said worm provided with a beveled driven gear, a pair of beveled driving gears disposed in opposed coacting relation with said beveled driven gears and provided with opposed clutch elements, a driving clutch element mounted between said driven clutch elements for neutral positioning or selective engagement therewith, a bearing mounted on said worm shaft, a pulley provided with a hub rotatable on said bearing and having a cam engagement therewith whereby rotation of the pulley imparts axial movement thereto, a shifting lever for said driving clutch member, a link connecting said pulley hub to said shifting lever, and a steering wheel having cable connection to said pulley.

5. The combination of a propeller provided with a rotatable support, a worm gear on said propeller support, a driving worm coacting therewith, a shaft for said worm provided with a beveled driven gear, a pair of beveled driving gears disposed in opposed coacting relation with said beveled gears and provided with opposed clutch elements, a driving shaft for said driving gears, a driving clutch element mounted on said driving shaft between said driven clutch elements for neutral positioning or selective engagement therewith, a bearing mounted on said worm shaft provided with a projecting pin, a pulley provided with a hub rotatable on said bearing and having a cam slot coacting with said pin whereby rotation of the pulley imparts axial movement thereto, a shifting lever for said driving clutch member, a link connecting said pulley hub to said shifting lever, a steering member having cable connection to said pulley, and an indicator comprising spindles each provided with a pointer and each having indicia associated therewith, driving connections for said spindles, and a driving connection for said worm shaft to said spindles whereby the forward position of the propeller is indicated by one pointer and the other pointer indicates its reversing positions, said pointers being arranged so that one is covered when the other is exposed.

6. The combination of a propeller provided with a rotatable support, a worm gear on said propeller support, a driving worm coacting therewith, a shaft for said worm provided with a beveled driven gear, a pair of beveled driving gears disposed in opposed coacting relation with said beveled gears and provided with opposed clutch elements, a driving shaft for said driving gears, a driving clutch element mounted on said driving shaft between said driven clutch elements for neutral positioning or selective engagement therewith, a bearing mounted on said worm shaft provided with a projecting pin, a pulley provided with a hub rotatable on said bearing and having a cam slot coacting with said pin whereby rotation of the pulley imparts axial movement thereto, a shifting lever for said driving clutch member, a link connecting said pulley hub to said shifting lever, and a steering member having cable connection to said pulley.

7. The combination of a propeller provided with a support rotatable through 360° on an axis perpendicular to the axis of the propeller, means for rotating said propeller support comprising a reversing gearing including a shiftable reversing element having a neutral position, and driving connections for said reversing gearing to said propeller support including a shaft having a bearing thereon provided with a projecting pin, a pulley provided with a hub rotatable on said bear-

ing and having a cam slot coacting with said pin whereby rotation of the pulley imparts axial movement thereto, a shifting lever for said reversing element member, a link connecting said pulley hub to said shifting lever, a steering member having cable connections to said pulley, and an indicator comprising a casing having curved segmental oppositely disposed windows having indicia associated therewith, spindles mounted on said casing and each provided with a pointer disposed in the same relation thereon, each pointer being associated with one of the windows, meshing gears connecting said spindles whereby the pointers are driven in opposite directions, and a driving connection for said shaft to one of said spindle gears whereby the forward positions of the propeller are indicated by one pointer throughout a range of 180° and the other pointer indicates its reversing positions throughout a range of 180°.

8. The combination of a propeller provided with a support, means for rotating said propeller support comprising a reversing gearing including a shiftable reversing element having a neutral position, and driving connections for said reversing gearing to said propeller support including a shaft having a bearing thereon provided with a projecting pin, a pulley provided with a hub rotatable on said bearing and having a cam slot coacting with said pin whereby rotation of the pulley imparts axial movement thereto, a shifting lever for said reversing element member, a link connecting said pulley hub to said shifting lever, and a steering member having cable connections to said pulley.

9. The combination of a steering and reversing propeller provided with a support, means for rotating said propeller support comprising a reversing gearing including a shiftable reversing element having a neutral position, and driving connections for said reversing gearing to said propeller support, a steering member, means operatively connecting said steering member to said reversing element, and an indicator comprising a casing having curved segmental oppositely disposed windows having indicia associated therewith, spindles mounted on said casing and each provided with a pointer disposed in the same relation thereon, each pointer being associated with one of the windows, meshing gears connecting said spindles whereby the pointers are driven in opposite directions, and a driving connection for the driven element of said reversing gear to one of said spindle gears whereby the forward positions of the propeller are indicated by one pointer and the other pointer indicates its reversing positions.

10. The combination of a propeller provided with a rotatable support, means for rotating said propeller support comprising a reversing gearing including a shiftable reversing element having a neutral position, and driving connections for said reversing gearing to said propeller support including a shaft, a steering member, means operatively connecting said steering member to said reversing element, an indicator comprising spindles each provided with a pointer and each having indicia associated therewith, driving connections for said spindles, and a driving connection for said shaft to said spindles whereby the forward positions of the propeller are indicated by one pointer and the other pointer indicates its reversing positions, means associated with said pointers, so that one is covered when the other is exposed.

11. The combination of a propeller provided

with a rotatable support, means for rotating said propeller support comprising a reversing gearing including a shiftable reversing element having a neutral position, and driving connections for said reversing gearing to said propeller support including a shaft, a steering member, means operatively connecting said steering member to said reversing element, and an indicator comprising a pointer having indicia associated therewith, and a driving connection for said shaft to said pointer whereby the positions of the propeller are indicated.

12. The combination of a propeller provided with a rotatable support, means for rotating said propeller support comprising a reversing gearing including a shiftable reversing element having a neutral position, and driving connections for said reversing gearing to said propeller support including a shaft having a bearing thereon, a pulley rotatable on said bearing and having a pin and slot connection thereto, the slot being inclined so that on the rotation of the pulley on its bearing axial movement is imparted to the pulley, operating connections for said pulley to said reversing element, a steering member, a cable extending from said steering member around said pulley, an indicator comprising a pair of pointers, each having indicia associated therewith, driving connection for said pointers whereby they are simultaneously actuated, and driving connections from said shaft to said pointers, said driving connections being such that one pointer indicates forward positions of the propeller and the other reversing positions thereof, means associated with said pointers so that one pointer is covered when the other is exposed.

13. The combination of a propeller provided with a rotatable support, means for rotating said propeller support comprising a reversing gearing including a shiftable reversing element having a neutral position, and driving connections for said reversing gearing to said propeller support including a shaft, a steering member, operating connections for said steering member to said reversing element, an indicator comprising a pair of pointers, each having indicia associated therewith, driving connections for said pointers whereby they are simultaneously actuated, and driving connections from said shaft to said pointers, said driving connections being such that one pointer indicates forward positions of the propeller and the other reversing positions thereof, means associated with said pointers so that one pointer is covered when the other is exposed.

14. The combination of a propeller provided with a rotatable support, means for rotating said propeller support comprising a reversing gearing including a shiftable reversing element having a neutral position, and driving connections for said reversing gearing to said propeller support including a shaft having a bearing thereon, a pulley rotatable on said bearing and having a connection thereto whereby on the rotation of the pulley on its bearing axial movement is imparted to the pulley, operating connections for said pulley to said reversing element, a steering member, a cable connecting said steering member to said pulley, an indicator comprising a pair of pointers,

each having indicia associated therewith, driving connections for said pointers whereby they are simultaneously actuated, and driving connections from said shaft to said pointers, said driving connections being such that one pointer indicates forward positions of the propeller and the other reversing positions thereof.

15. The combination of a propeller provided with a rotatable support, means for rotating said propeller support comprising a reversing gearing including a shiftable reversing element having a neutral position, and driving connections for said reversing gearing to said propeller support including a shaft having a bearing thereon, a pulley rotatable on said bearing and having a connection thereto whereby on the rotation of the pulley on its bearing axial movement is imparted to the pulley, operating connections for said pulley to said reversing element, a steering member, and a cable connecting said steering member to said pulley.

16. The combination of a propeller provided with a rotatable support, means for rotating said propeller support comprising a reversing gearing including a shiftable reversing element having a neutral position, and driving connections for said reversing gearing to said propeller support, a rotatable and axially movable pulley, means for moving said pulley axially on the rotation thereof, operating connections for said pulley to said reversing element, a steering member, a cable connecting said steering member to said pulley, an indicator comprising a pair of pointers, each having indicia associated therewith, and driving connections for said pointers to said driving connection for said reversing gearing to said propeller support, said driving connections being such that one pointer indicates forward positions of the propeller and the other reversing positions thereof.

17. The combination of a propeller provided with a rotatable support, means for rotating said propeller support comprising a reversing gearing including a shiftable reversing element having a neutral position, and driving connections for said reversing gearing to said propeller support, a rotatable and axially movable pulley, means for moving said pulley axially on the rotation thereof, operating connections for said pulley to said reversing element, a steering member, and a cable connecting said steering member to said pulley.
